CONVERSION OF HYDROCARBON OIL

Edwin F. Nelson, Chicago, Ill., assignor to Universal Oil Products Company, Chicago, Ill., a corporation of Delaware

Application December 12, 1932, Serial No. 646,819

4 Claims. (Cl. 196—50)

This invention refers to an improved process and apparatus for the conversion of natural or casinghead gasoline for the purpose of producing motor fuel of wider boiling range than the charging stock and of high anti-knock value.

Natural gasoline, which is the liquid petroleum product recovered by compression, absorption or other means from natural gas, is used primarily for blending with less volatile distillates to produce composite motor fuel. The usual resulting blended motor fuel does not have the even chain of boiling points and the high anti-knock value required for high motor fuel efficiency and with the rapid adoption of modern cracking processes producing high yields of premium motor fuel for modern high compression engines, the demand for natural gasoline as blending material is rapidly diminishing.

The present invention anticipates another use for natural gasoline, when its economic value as a blending fluid has become of minor importance, by providing an improved process and apparatus for the pyrolytic conversion of natural gasoline to produce a motor fuel of a wider boiling range and of high anti-knock value.

I have found that the methods of cracking employed by the best present day processes for the conversion of relatively low boiling oils, wherein the high boiling intermediate conversion products are returned to further conversion together with the charging stock, are not the most suitable for the conversion of natural gasoline. This method of operation as applied to the treatment of natural gasoline results in the production of high yields of gas and high yields of intermediate gasoline fractions leaving the motor fuel product of the process deficient in high boiling fractions.

The present invention overcomes this difficulty by recovering the high boiling motor fuel fractions produced by once-through treatment of the charging stock instead of returning a high percentage of such material as reflux condensate to the heating coil for further conversion. The present process is further improved over the usual cracking operation by returning the excess quantity of intermediate motor fuel fractions to further conversion together with the charging stock under conditions which effect their conversion into substantial quantities of lower and higher boiling motor fuel fractions.

A more specific embodiment of the present invention may comprise subjecting natural gasoline to conversion at elevated temperature and super-atmospheric pressure, separating from the resulting vaporous conversion products the relatively

low boiling and the relatively high boiling motor fuel fractions, returning a portion of the intermediate boiling motor fuel fractions also recovered by said fractionation to further conversion together with the natural gasoline charging stock to produce additional yields of low boiling and high boiling fractions, and finally commingling said low boiling and high boiling motor fuel fractions as the final motor fuel product of the system.

It is also within the scope of the present invention as an optional feature of the operation of the process, to return any intermediate conversion products boiling above the end boiling point of the desired motor fuel product and below the high coke forming residual conversion products of the process to further conversion together with the charging stock and the intermediate motor fuel fractions.

The accompanying diagrammatic drawing illustrates one specific form of apparatus for carrying out the present invention although it should be understood that many other specific forms of apparatus are suitable for the practice of the process of the present invention and that the invention is not limited by the specific form of apparatus illustrated.

Referring to the drawing, natural gasoline, which comprises the raw oil charging stock for the system, is supplied through line 1 and valve 2 to pump 3 from which it is fed through line 4 and valve 5 to heating coil 6, which is located in the furnace 7 of any suitable form and by means of which the oil is heated to the desired conversion temperature preferably at a substantially superatmospheric pressure. It will be understood that the charging stock may, when desired, be preheated in any well known manner, not illustrated in the drawing, prior to its introduction into the heating coil.

The heated oil is discharged from the heating coil 6 through line 8 and valve 9 into reaction chamber 10, which is also preferably maintained at a substantial superatmospheric pressure, and, although not illustrated in the drawing, it is preferably well insulated to prevent the excessive loss of heat by radiation so that continued conversion of the oil, and particularly its vaporous components, may be accomplished in this zone.

Both vaporous and residual liquid conversion products are withdrawn from a lower portion of chamber 10 through line 11 and valve 12 and are introduced into fractionator 13 which in the case illustrated, serves as both a fractionating and separating column. Any heavy residual liq-

uid produced by the operation, unsuitable for further conversion with the charging stock, may be withdrawn from the lower portion of fractionating and separating column 13 through line 14 and valve 15 to cooling and storage or to any desired further treatment. Uncondensable gas and lower boiling motor fuel fractions produced by the operation are withdrawn as the vaporous stream from the upper portion of the fractionator 5 through line 16 and valve 17 to be subjected to condensation and cooling in condenser 18, from which the resulting distillate and uncondensable gas passes through line 19 and valve 20 to collection in receiver 21. Uncondensable gas may 10 be released from the receiver through line 22 and valve 23. The distillate collecting in receiver 21 may be removed through line 24 and valve 25. When desired, a portion of the distillate from receiver 21 may be recycled as a cooling and re- 15 flux medium to the upper portion of fractionator 13, by well known means not shown in the drawing, for the purpose of regulating the vapor outlet temperature from the fractionator and controlling the end boiling point of said low boiling 20 fraction. The high boiling motor fractions produced by the operation are withdrawn as a side stream from the fractionator from a suitable point, for example, through line 26 and valve 27 to cooler 28, from which they are withdrawn 25 to line 29 and valve 30 or through line 29' and valve 30' to be blended with the low boiling motor fuel fractions recovered as distillate in receiver 21, the blended product forming the final 30 motor fuel product of the system.

35 A portion of the intermediate motor fuel fractions, comprising that portion of the material boiling substantially above the initial boiling point and substantially below the end boiling point of the desired final motor fuel product 40 which are produced in quantities in excess of those required for a motor fuel product of even burning characteristics, is removed from a suitable intermediate point in the fractionator, for example through line 31 and valve 32 to pump 33, to be 45 returned therefrom through line 34, valve 35 and line 4 to heating coil 6 for further conversion together with the charging stock.

When the operation produces any substantial 50 quantity of material boiling above the end boiling point of the desired motor fuel product which may be subjected to further conversion in the heating coil for the production of substantial 55 quantities of additional motor fuel fractions without the excessive production of coke and gas, this material may, instead of being blended with the residual liquid withdrawn, as already described, through line 14 and valve 15, be removed as a 60 separate fraction from the fractionator, for example, through line 36 and valve 37 into line 31 and thence to pump 33 to be returned to further 65 conversion in heating coil 6 through line 34, valve 35 and line 4, together with the intermediate motor fuel fractions and the natural gasoline charging stock.

65 The conversion conditions most suitable for the production of maximum yields of motor fuel of the desired wide boiling range and of high anti-knock value will vary for natural gasoline charging stocks of different grades and characteristics 70 but may range, for example, from 950 to 1100° F., or thereabouts with a superatmospheric pressure of from 500 to 1000 pounds or thereabouts per square inch. In a system such as above illustrated and described these conditions apply to 75 the temperature and pressure employed at the

outlet from the heating coil while substantially the same or somewhat reduced pressure may be employed in the reaction chamber. A substantially reduced pressure ranging from 100 pounds or thereabouts, per square inch, down to substantially atmospheric or when desired, superatmospheric pressure substantially equalized with that in the reaction chamber may be employed in the succeeding separating, fractionating, condensing and collecting portions of the system.

As an example of one specific operation of the process of the present invention utilizing as charging stock a natural gasoline containing about 40% of material boiling up to 140° F., it is subjected in the heating coil to a temperature of 15 about 1000° F., at a superatmospheric pressure of approximately 800 pounds per square inch and substantially the same pressure is maintained in the reaction chamber. The vaporizing, fractionating, condensing and collecting portions of the system are operated at a superatmospheric pressure of about 100 pounds per square inch. Low boiling motor fuel fractions removed as the overhead vaporous products from the fractionator comprise distillate boiling up to approximately 220° F. The high boiling fractions of the motor fuel product separately withdrawn from the fractionator comprise materials boiling between approximately 220 and 400° F. The excess production of intermediate motor fuel fractions, 30 boiling up to approximately 325° F., is returned to further conversion in the heating coil together with the charging stock and with another stream of intermediate fractions from the fractionator boiling between approximately 400 to 550° F. 35 This operation may yield, per barrel of charging stock, about 77% of motor fuel with an end boiling point of approximately 400° F., and an anti-knock value equivalent to an octane number of approximately 80. The additional products of 40 the system are uncondensable gas, a small quantity of residual oil and a negligible amount of coke.

I claim as my invention:

1. A process for treating casinghead gasoline 45 to produce motor fuel of wider boiling range and high anti-knock value which comprises heating the gasoline to a temperature adequate to increase the anti-knock value thereof, fractionating the resultant vapors and separating therefrom a light 50 gasoline fraction, a heavy gasoline fraction, and an intermediate gasoline fraction boiling between the light and heavy fractions, returning the intermediate fraction to the heating step for re-treatment in admixture with an additional quantity of the casinghead gasoline, combining said light and heavy fractions and recovering the resultant blend as the product of the process.

2. A process for treating casinghead gasoline 60 to produce motor fuel of wider boiling range and high anti-knock value which comprises heating the gasoline to a temperature adequate to increase the anti-knock value thereof, fractionating the resultant vapors and separating the same into a reflux condensate composed of hydrocarbons 65 heavier than gasoline, a light gasoline fraction, a heavy gasoline fraction, and an intermediate gasoline fraction boiling between the light and heavy fractions, returning the intermediate fraction and the reflux condensate to the heating step 70 for re-treatment in admixture with an additional quantity of the casinghead gasoline, combining said light and heavy fractions and recovering the resultant blend as the product of the process.

3. A process for treating casinghead gasoline 75 to produce motor fuel of wider boiling range and

high anti-knock value which comprises heating the gasoline to a temperature adequate to increase the anti-knock value thereof, fractionating the resultant vapors and separating therefrom a light fraction boiling up to about 220° F., an intermediate fraction boiling up to about 325° F., and a heavy fraction having an end boiling point of about 400° F., returning the intermediate fraction to the heating step for retreatment in admixture with an additional quantity of the casing-head gasoline, combining said light and heavy fractions and recovering the resultant blend as the product of the process.

4. The process as defined in claim 3 further characterized in that a reflux condensate heavier than gasoline is also separated from said vapors during the fractionation step and returned to the heating step with the intermediate fraction. 5

EDWIN F. NELSON. 10
